(57) **CLAIM**

The ornamental design for a golf club head, as shown and described.

DESCRIPTION

Reference is now made to the accompanying drawing which forms a part of this application. The drawing of this application illustrates, in dotted, phantom lines, a rear view of a golf club head having inventive, two or three dimensional design elements shown in solid black demarcations.

FIG. 1 is an elevational view of the claimed design.

The phantom lines in the drawing figures form no part of the claimed design, but are intended to illustrate the environment of the inventive design shown in solid black demarcations.
